UNITED STATES PATENT OFFICE.

JACOB BOESEL, OF CLEVELAND, OHIO.

DESIGN FOR AN IRONING-BOARD.

SPECIFICATION forming part of Design No. 30,286, dated February 28, 1899.

Application filed January 16, 1899. Serial No. 702,371. Term of patent 7 years.

To all whom it may concern:

Be it known that I, JACOB BOESEL, of Cleveland, county of Cuyahoga, State of Ohio, have invented and produced a new and original 5 Design for Ironing-Boards, of which the following is a specification, reference being had to the accompanying drawings, forming part thereof.

Figure 1 is a side view of the board, showing my new design. Fig. 2 is also a side view of the same.

As shown in the drawings, the leading or material features of my design consist in the complete design, as presented, of upper and lower portions and connection between them. 15 The upper portion has straight parallel sides at 4, extending for half its length, and circular extremities 6 and 7 at either end, one end 7 being smaller than the other. This extremity is provided with tapering sides 9, which are connected with the parallel sides by means 20 of ogee curves 10. The lower portion of the

board is provided with parallel sides for about one-half of the length and with circular extremities 11 and 12, one extremity 11 25 being larger than the other. The smaller semicircular extremity 12 is connected with the parallel sides by means of straight lines 13, thus giving a taper to this half of the board. The connection between the upper 30 and lower portions of the board is X-shaped and placed centrally between them.

Having described my invention, what I claim as new, and desire to secure by Letters Patent, is—

The design for an ironing-board as shown and described.

Signed by me, at Cleveland, this 5th day of January, A. D. 1899.

JACOB BOESEL.

Attest:

W.M. M. MONROE,
